UNITED STATES PATENT OFFICE.

CARL GUGGENBUEHLER, OF NEWARK, NEW JERSEY.

TOOL FOR FACILITATING THE CASTING OF HUB-LINERS ON BEARING-BOXES FOR LOCOMOTIVES OR THE LIKE.

1,344,083.

Specification of Letters Patent. Patented June 22, 1920.

Application filed June 6, 1919. Serial No. 302,216.

To all whom it may concern:

Be it known that I, CARL GUGGENBUEHLER, a citizen of Germany, residing at Newark, in the county of Essex and State of New Jersey, have invented certain new and useful Improvements in Tools for Facilitating the Casting of Hub-Liners on Bearing-Boxes for Locomotives or the like, of which the following is a specification.

10 This application is an improvement on the application Serial No. 206,320, filed December 8, 1917 and which on July 2, 1918 matured into Letters Patent No. 1,271,310.

15 The present invention relates to means for facilitating the casting of liners of brass or babbitt on so-called truck boxes or driving boxes of axle bearings for locomotives or the like, which liners usually are employed to fill the gap or space between the 20 hub of a wheel and its bearing box.

According to the hitherto used methods of applying such liners, the box is clamped in a planing machine and the liner which has been first cast into the proper shape is 25 screwed to the box and then planed to the desired thickness. Such method obviously renders the work more or less complicated requiring separate help for casting and planing the liner. It also is objectionable because 30 much waste of material is occasioned since the scrapings of the expensive metal falling to the ground become mixed with dust and other materials. If it is desired to recuperate the metal additional labor is required for separating the scrapings from 35 the mixture. But the metal even thus recuperated when heated again loses its resisting power and becomes practically valueless.

40 The object of my invention is therefore to do away with these drawbacks and to provide means whereby considerable labor can be saved and waste eliminated.

I accomplish this object by providing a 45 device which can be easily and readily removably applied to the hub end of the bearing and which will form a sort of mold to receive the molten material whereby the liner will be cast directly onto the box to 50 be at once of the desired dimensions without requiring any subsequent finishing work.

This invention deals particularly with a 55 device designed for forming hub liners on driving wheel boxes which ordinarily have also inner liners, the thickness of which

varies according to wear. It is therefore another object of my invention to provide means which will enable the device to be adjusted according to the particular size or thickness of the inner liner of such boxes. 60

With these and other objects in view my invention consists in the construction, arrangement and combination of parts as will be hereinafter more fully described and set forth in the appended claims. 65

Reference is had to the accompanying drawing in which similar reference characters denote corresponding parts and in which Figure 1 is a bottom view of a driving wheel box having an inner liner and resting on one of its end faces and with the opposite end face directed upwardly showing my new device applied thereto to form the hub liner; Fig. 2 is a longitudinal section on line 2—2 of Fig. 1; Fig. 3 is a top 75 plan view of the tool and Fig. 4 is a bottom plan view thereof.

Referring in detail to the drawing 10 denotes the driving wheel box of the usual construction and shape as used for locomotive axles and provided with the inner liner 10'. 80

The device for forming the hub liner 10² comprises an iron or steel plate 11 of substantially rectangular shape and corresponding in height and width with those of the end face of the box to which the hub liner is to be applied. This plate may be composed of superposed layers or sections as the corresponding plate in my above named Letters Patent, or may be made, as shown, in one piece. The bottom of the plate has an even and smooth surface and is provided centrally with a substantially crescent shaped groove 12, the outer wall 12' of 95 which is cylindrical and the inner wall 12² is shaped according to the shape of the inner liner 10'. In the present example where the inner liner is assumed to be cylindrically rounded the inner wall 12² is correspondingly shaped. The groove 12 is so admeasured that when the plate 11 is placed onto the end face of the box 10 the inner wall will normally coincide with the inner surface of the liner 10', while the outer wall will extend a certain distance away therefrom to cover a part of the end face of the box, the groove 12 being adapted to surround three sides of the hollow of the box. 100

The outer face of the plate 11 may be 110

formed with handles (not shown) similar to those shown and described in my aforementioned Letters Patent.

For securing the plate 11 in position on the box 10, I provide suitable clamping means. Although I may use clamping means similar to those shown and described in my said Letters Patent, I prefer the following construction which I found to be 10 more effective:

Fixed to the upper face of the plate 11 are laterally and downwardly projecting members 13 two on each side thereof, which are in form of angular arms. The lower horizontal parts of these arms which project toward the box carry clamping screws 14 adapted to extend between the flanges 10³ and 10⁴ on each side of the box. These screws are made of such a length that when turned in one direction they will engage the flanges 10³ located immediately below the plate 11 and clamp the latter in position, but when it is desired to lift the plate 11 from the box and the said screws are turned 20 in opposite direction they will, with their heads 14', engage and press against the opposite flanges 10⁴ of the box as indicated by dotted lines in Fig. 1 and thereby lift the plate 11.

Since the inner liner by reason of wear varies in thickness it is necessary to provide suitable means to allow of the corresponding adjustment thereof. To this end I provide an adjustable member or core 15 30 the outer face of which corresponds with the shape of the inner wall 12² or inner liner 10' and therefore may be rounded as shown in Fig. 4, or may be angular similar to the stationary core 21 in my said Letters Patent.

The core 15 may be hoof shaped as shown or 40 may be a solid piece. This member or core is centrally fixed to a rod 16 and is provided on its upper or inner surface with a number of upwardly extending threaded bolts 45 17 which through guide holes 11' made in the plate 11 project beyond the upper surface of the latter. The threaded ends of said bolts receive clamping nuts 18 whereby the core after its adjustment into the proper

50 position can be clamped to the plate 11. The rod is adapted to extend over the bottom or inner surface of the plate 11 and has its rear end 16' threaded and rotatively borne in a bearing 19 fixed to the plate at 55 19'. Working on the free end of the rod 16 is a nut 20 which is provided with a handle 20' by the manipulation of which the rod 16 is fed inwardly or outwardly as the case may be and whereby the member 15 60 can be adjusted according to the thickness of the inner shell or liner 10'. A spiral spring 21 mounted around the rod 16 and suitably fixed between the same and the bracket or bearing 19 serves to bring about 65 a tight closure between the member 15 and

the inner liner or shell 10'. 22, 22 denote charge holes through which the molten metal is cast into the hole or mold 12.

If the inner shell or liner 10' of the box has been worn, the member or core 15 will 70 have to be moved more inwardly until it will bear tightly against the inner surface of the said liner 10' before the hub liner 10² can be cast.

The mode of using my new device is as 75 follows:—

The plate 11 is placed onto the end of the box on which the hub liner is to be cast so that the core 15 extends through the said end into the hollow of the box. The plate 80 is then clamped in position by the clamping screws 14 carried by the lateral members 13. Thereupon the core or member 15 is adjusted by means of the nut 20 so as to tightly 85 fit against the inner surface of the liner 10' and is secured in that position by the tightening nuts 18. In the example shown the inner liner is shown somewhat worn so that the core, when adjusted, projects inwardly 90 beyond the inner wall 12² of the mold. 95 Thereupon the metal is cast through the charge holes 22 to fill the mold 12 (Fig. 2). After the molten metal has been allowed to cool the tool is removed from the box in the following manner:—

On loosening the nuts 18 the head or core 15 is first moved back to its initial position by the manipulation of the handle 20' until it clears the metal covering it as shown in Fig. 2. Thereupon the clamping screws 14 100 are unscrewed until their heads 14' are brought into contact with and press against the opposite flanges 10⁴ of the box, whereby the plate 11 is forced upwardly clearing the box and hub liner 10². The only additional 105 work that may be necessary when the inner liner is worn is to cut off and round off the edge of the hub liner 10² projecting beyond the inner surface of the inner liner 10'.

With this device it is thus obvious the hub 110 liners can be readily cast without any waste of material and with considerably little labor.

Since the construction may be modified in numerous ways without deviating from the 115 principle of my invention, I do not wish to restrict myself to the details shown and described.

What I claim and desire to secure by Letters Patent is:—

1. The combination with a bearing box for locomotives or the like, of a device for casting a hub liner thereon, and comprising a mold capable of being removably attached to the hub end of said box to receive the 125 molten metal and having a movable core adjustable relative to said mold.

2. The combination with a bearing box for locomotives or the like, of a device for casting a hub liner thereon, and comprising a 130

mold having a movable core adjustable relative to the mold and means for the removable attachment of said mold to the hub end of said box.

5. 3. The combination with a bearing box for locomotives or the like, of a device for casting a hub liner thereon, comprising a mold having a movable core adjustable relative to the mold, means for the removable attachment of said mold to the hub end of said box and means for the adjustment of said core.

10. 4. The combination with a bearing box having an inner liner, of a device for casting a hub liner thereon, comprising a mold capable of being removably attached to the hub end of said box and having a movable core and means for the adjustment of said core relative to said mold to closely fit the

20 inner liner of said box.

5. The combination with a bearing box having an inner liner, of a device for casting a hub liner thereon, comprising a plate adapted to fit on the hub end of the said box 25 and having a groove in its bottom serving as a mold, a movable core adjustable relative to said mold to fit said inner liner and means for the removable attachment of said plate to said box.

30. 6. The combination with a bearing box having an inner liner, of a device for facilitating the casting of a hub liner thereon, comprising a plate adapted to fit the hub end of the box and formed in its bottom with a 35 groove corresponding in shape and size with the liner to be cast and having charge openings, a movable core adjustable relative to said groove and adapted to engage the hollow of the box and to fit the inner liner and

40 means for the removable attachment of said plate to said box.

7. The combination with a bearing box having an inner liner, of a device for facilitating the casting of a hub liner thereon, 45 comprising a plate adapted to fit the hub end of the box and formed in its bottom with a substantially crescent shaped groove, the dimensions of which correspond to those of the hub liner to be cast, a core adjustably supported on the bottom of said plate and the outer face of which corresponds in shape with that of the inner liner, and clamping means supported by said plate and serving for the removable attachment of the latter to

55 the box.

8. The combination with a bearing box

having an inner liner, of a device for facilitating the casting of a hub liner thereon, comprising a plate adapted to fit the hub end of a box and having in its bottom a centrally arranged groove, said groove having charge openings and serving as a mold, a member or core adjustably supported on the bottom of the plate and adapted to engage the hollow of the box and to fit the inner 60 liner, means for guiding and fixing said member or core in adjusted position and means for clamping said plate to said box.

9. The combination with a bearing box having flanges at its ends, of a device for 70 facilitating the casting of a hub liner thereon, comprising a plate adapted to fit on the hub end of the box and having a groove in its bottom serving as a mold and having charge openings from and clamping screws 75 supported from said plate and working between the opposite flanges of the box so that by turning said screws in one direction toward the flanges at the hub end of the box the said plate becomes clamped to the latter 80 and by turning said screws toward and against the opposite flanges the said plate is lifted from the said box.

10. A device for facilitating the casting of a hub liner in a bearing box having an 85 inner liner, comprising a plate adapted to fit on the hub end of the box and formed in its bottom with a substantially crescent shaped groove serving as a mold and having charge openings, a core supported on the 90 bottom of the said plate and adapted when the latter is mounted on the box to engage the hollow thereof and to fit the said inner liner, means for adjusting said core to snugly fit against the said inner liner and means 95 for the removable attachment of said plate to said box.

11. A device for facilitating the casting of a hub liner on a bearing box, comprising a plate having a groove serving as a mold, a 100 core movable across said groove, manually operated means for adjusting said core relative to said groove, means for guiding and fixing said core in adjusted position and means for the removable attachment of said 105 plate from said box.

In testimony whereof I affix my signature in presence of two witnesses.

CARL GUGGENBUEHLER.
